UNITED STATES PATENT OFFICE

GUSTAVE M. NELL, OF DETROIT, MICHIGAN, ASSIGNOR TO CHICAGO PNEUMATIC TOOL COMPANY, OF NEW YORK, N. Y., A CORPORATION OF NEW JERSEY

FLUID PRESSURE TOOL

Application filed February 1, 1929. Serial No. 336,880.

This invention relates to fluid pressure motors of the type embodied in percussive machines generally, of which pneumatic hammers and hammer drills are the more common examples. More particularly it relates to tools and machines using motors in which the distribution of the motive fluid is controlled by a valve thrown automatically in timed relation with the movements of the piston.

One object of the invention is to provide an improved form of percussive motor having a simple, compact and easily assembled valve structure. Another object is to dispose the valve structure concentric with the main operating parts of the machine thereby to avoid the customary large projection which makes such machines awkward to handle and to operate. Another object is to provide for exact determination of the quantity of motive fluid passing to the ends of the piston chamber. Still another object is to effect accurately timed and positive movement of the valve. Other objects will be apparent from the detailed description which follows.

In order to illustrate the invention one concrete embodiment thereof and certain modified forms of the valve are shown in the accompanying drawings in which:

Fig. 1 is a longitudinal sectional view of a percussive drill;

Fig. 2 is a sectional view of a detail of Fig. 1, namely the valve assembly and indicating a slight modification of the valve, the section being taken substantially on the line 2—2 of Figs. 3 and 4;

Figs. 3 and 4 are respectively left and right end elevational or plan views of the valve assembly shown in Fig. 2;

Fig. 5 is a sectional view substantially on the line 5—5 of Fig. 2 showing a modification of the valve; and

Fig. 6 is a sectional view similar to Fig. 5 showing the valve of Fig. 1.

In the embodiment of the invention chosen for the purpose of illustration the cylinder 7 of the percussive drill has an atmospheric exhaust port 8 intermediate its length arranged to be overrun and controlled by the hammer piston 9 which is reciprocated within the pis-

ton chamber of the cylinder to impart blows to a suitable working tool such as a drill steel 10. The steel is supported for rotation in the chuck 11 in front head 12 and may be hollow to permit cleansing fluid to be fed thereto through the usual tube 13 extending axially through the drill.

The rearward end of cylinder 7 is counterbored to receive and to support, in line with the piston chamber, a valve assembly which preferably comprises valve case 14, valve lid 15, and valve 36. In the form shown, a ratchet ring 17 is also inserted within the counterbore of cylinder 7 against the valve chest to support the head of a rifle bar 18, the bar portion of which extends through aligned bores 15a and 14a of parts 15 and 14 comprising the valve chest. A back head 19, in which tube 13 is preferably supported, engages ring 17 to hold the same and the valve assembly in place in the cylinder, the back head being in turn held in place by any suitable means such as the usual side rods or through bolts (not shown).

As indicated, case 14 and lid 15, comprising the valve chest, provide therewithin a valve chamber which in the present instance is annular in shape. An annular series of ports 20 open through one end wall of the valve chamber, namely, through case 14 (Figs. 1, 2, and 4) into the rear end of the piston chamber. A complementary series of ports 21 in the opposite end wall of the valve chamber, namely lid 15, open into passages 21a which extend radially and then make a right-angular turn in a forward direction and register with connecting passages 21b in case 14, and 21c in cylinder 7, to enter the piston chamber at the forward end thereof. Ports 20 and 21 are controlled by a suitable valve such as 36, which has end faces 36a and 36b for this purpose, and provide therebetween, within the valve itself, a chamber for pressure fluid. The valve is shown as annular in shape and mounted for movement entirely within the confines of case 14. The valve may have a bearing or sliding fit with case 14 either on the inner or outer peripheral wall of the valve chamber. In Fig. 2, valve 16 slidably engages only the central boss of case 14, which

boss is made hollow or perforate by reason of the bore 14a. The valves 26 of Fig. 5 and 36 of Figs. 1 and 6, have a sliding fit or bearing upon both the inner and outer peripheral walls of the valve case 14.

Pressure fluid is supplied to the central chamber of valves 16, 26, or 36 from inlet 22 in the back head 19 which communicates with an annular chamber 22a in the face of the head adjacent ring 17. An annular series of passages 22b extend through ring 17 and register with similar passages 22c of case 14, the latter passages taking a right-angular bend to open into the valve chamber substantially centrally thereof. The motive fluid in the central chamber of the valve is distributed alternately to ports 20 and 21 at the ends of the valve chamber depending upon the position of the valve. Means are provided, however, for restricting the volume of motive fluid to an amount less than the capacity of the ports at each end of the valve chamber. In the form of the valve shown in Fig. 2, this is accomplished by extending the end faces almost to the outer wall of the valve chamber but leaving a narrow peripheral passage, the extent of which is indicated by the space between the two adjacent broken lines shown in Fig. 3. In Fig. 5 the same result is accomplished with valve 26 by the provision of a series of notches 26a in the periphery thereof. Still another variation is shown in Fig. 6 wherein the passage of motive fluid through the end faces of valve 36 is provided for by a series of ports 36a adjacent the outer edge of the same.

The operation of the tool shown in Fig. 1 is briefly as follows: With the parts in the position shown, motive fluid is passing from the central chamber of the valve through ports 36a in face 16b to ports 21 and thence by passages 21a, 21b, and 21c to the forward end of the piston chamber to drive piston 9 rearwardly, the rear end of the piston chamber being open to exhaust through port 8, and ports 20 of the valve chest being sealed by face 16a of the valve. As the piston moves rearwardly, it closes exhaust 8 trapping a quantity of air in the piston chamber and compressing the same. The air thus compressed acts through ports 20 against face 36a of the valve. When the piston 9 has moved far enough to uncover port 8 and open the forward end of the piston chamber to atmosphere, there is a sudden drop in pressure in passages 21c, 21b, 21a and ports 21 with the result that the valve moves quickly to its rearward position closing ports 21. The motive fluid from the central valve chamber now passes through face 36a to ports 20 driving the piston forwardly. As central exhaust 8 is closed by piston 9, pressure begins to build up in passages 21c, 21b, and 21a and this pressure becomes effective to shift the

valve back to its original position when piston 9 uncovers exhaust 8, as shown in Fig. 1.

The restriction in the movement of motive fluid from the central valve chamber to the end ports, accomplished in any one of the ways indicated in Figs. 2, 5, and 6, is of importance in the shifting movement of the valve since it prevents the passing of motive fluid in sufficient quantity to the exhaust side of the valve to interfere with the movement of the same. The effective pressure for throwing the valve is increased by enlarging ports 20 and 21 where they open into the valve chamber by flaring or counter-sinking the same as indicated at 20a and 21a, Figs. 1 and 2. If desired, the throwing pressure may also be increased by providing one or more restricted ports through each of the end faces of the valve as indicated at 16c in Fig. 2. Similar ports for the same purpose may be provided in the modifications of the invention as indicated at 26c and 36c in Figs. 5 and 6 respectively. Alternatively or additionally the outer end faces of the valves may be reduced or cut away toward their periphery, as indicated at 16d (Fig. 2), to provide annular relief areas supplied from the central chamber of the valve. This arrangement minimizes the intensity of the pressure necessary to start the valve off its seat.

To maintain the control parts of the drill so that the communicating passages will always be in register, long dowel pins 23 are provided which extend through suitable bores therefor in ring 17, lid 15, and case 14 and have their ends received in suitable sockets in cylinder 7 and back head 19 respectively.

While the invention has been herein disclosed in what is now considered to be a preferred form with modifications, it is to be understood that the invention is not limited to the specific details thereof but covers all changes, modifications, and adaptations within the scope of the appended claims.

I claim as my invention:

1. In a fluid pressure motor, a cylinder having an exhaust port intermediate its length, a piston reciprocable in said cylinder and controlling said port, a valve chest in line with the piston chamber and serving as a closure for the latter, said chest providing an annular valve chamber and having ports at the ends thereof leading to opposite ends of the piston chamber, an annular valve having end faces for controlling the ports in said valve chest and an intermediate reservoir for pressure fluid, and means comprising ports in the end faces of said valve restricting the movement of pressure fluid from said reservoir to each group of end ports in said valve chamber to an amount less than the capacity of each group.

2. In a fluid pressure motor, a cylinder having an exhaust port intermediate its length, a piston reciprocable in said cylinder

and controlling said port, a valve chest in line with the piston chamber and serving as a closure for the latter, said chest providing an annular valve chamber and having ports at 5 the ends thereof leading to opposite ends of the piston chamber, an annular valve having end faces for controlling the ports in said valve chest and an intermediate reservoir for pressure fluid, and means comprising ports 10 in the end faces of said valve restricting the movement of pressure fluid from said reservoir to each group of end ports in said valve chamber to an amount less than the capacity of each group, said valve ports being 15 out of register with said chest ports in all positions of said valve.

3. In a fluid pressure motor, a cylinder having an exhaust port intermediate its length, a piston reciprocable in said cylinder 20 and controlling said port, a valve chest in line with the piston chamber and serving as a closure for said cylinder, said chest providing an annular valve chamber and ports at the opposite ends thereof leading to opposite 25 ends of the piston chamber, an annular valve providing end faces for controlling the ports in said valve chest, and an intermediate reservoir for pressure fluid, said valve having ports out of register with said chest ports 30 but arranged to permit the passing of pressure fluid from said reservoir alternately to each end group of chest ports in less volume than the capacity of each end group, said valve being moved by air compressed by the 35 piston at the end of each stroke and having at least one restricted port through each end face to permit a limited amount of pressure fluid from said reservoir to reach the closed ports and augment the air compressed by the 40 piston.

4. In a fluid pressure motor having a cylinder and a piston reciprocable therein, a valve chest providing an annular valve chamber and ports at the opposite ends thereof 45 leading to opposite ends of the piston chamber, and an annular valve having end faces for controlling said ports and providing an intermediate reservoir for pressure fluid, said valve slidably engaging both the inner 50 and outer walls of said chest and having means for passing pressure fluid from said reservoir to said ports in alternation, said last mentioned means being of lower capacity than said ports.

55 Signed by me at Detroit, in the county of Wayne, and State of Michigan, this 28th day of January, 1929.

GUSTAVE M. NELL.
